[57] ABSTRACT

A rooftop tape storage rack comprising a unitary device having a bottom wall, spaced side walls, and an end wall, one side wall having an opening therein for permitting cartridges to be inserted and removed, and a longitudinally extending slot in the bottom wall through which a finger can be inserted to raise a cartridge for removal through the opening in said one side wall. Means are associated with said device for fastening said device to the roof of an automotive vehicle.

FIG. 2

FIG. 3

FIG. 4

FIG. 1

ROOFTOP TAPE STORAGE RACK

This invention relates to storage of tape cartridges and particularly to storage of such cartridges in automobiles.

BACKGROUND OF THE INVENTION

In automobiles and the like, it has been common to incorporate tape decks which are used to play tape cartridges for the entertainment and amusement of the occupants of the automobile. One of the difficulties with respect to such devices is that cartridges must be stored, preferably out of the normal area of activity of the occupants.

Accordingly, among the objects of the invention are to provide a tape storage rack wherein cartridges can be stored adjacent the interior of the roof of the vehicle and readily accessible to the occupants; which is easily installed; which can be made at relatively low cost; which is aesthetically pleasing.

SUMMARY OF THE INVENTION

The rooftop tape storage rack embodying the invention comprises a unitary device molded from organic plastic material and having a top wall, side walls, end walls and a bottom wall. The side walls have a substantially lesser height than said end walls thereby forming an opening therein for receiving tape cartridges. The cartridges are adapted to be held in side-by-side relationship with the side walls engaging the ends of the cartridges. A slot is provided in the bottom wall and extends substantially throughout the length thereof providing a finger receiving opening through which a finger can be inserted to lift the cartridges for ready removal from the openings in said side walls. Laterally extending mounting panels extend from said end walls at the area of juncture of said end walls and said top wall to provide a means of attachment to the roof of the automotive vehicle.

DESCRIPTION OF THE DRAWINGS

FIG. 1 is a fragmentary diagrammatic view showing the tape storage rack embodying the invention in position in an automobile.

FIG. 2 is a side elevational view of the same.

FIG. 3 is a perspective view of the same.

FIG. 4 is a sectional view taken along the lines 4—4 in FIG. 2.

DESCRIPTION

Referring to the drawings, the tape storage deck 10 embodying the invention is adapted to be mounted on the inner surface of the roof 11 of a vehicle A and is made as a unitary device of organic plastic material such as acrylonitrile butadiene styrene plastic.

The rack 10 comprises a rectangular top wall 12 and a rectangular bottom wall 13 joined by end walls 14. Short side walls 15 extend upwardly from the bottom wall 13 and form flanges that define openings 16 through which tape cartridges can be inserted or removed. The bottom wall is formed with a longitudinally extending slot 17 and provides a finger receiving opening as presently described.

The rack further includes laterally extending integral panel portions 18 that lie in the plane of the top wall 12 and curved end portions 19 that extend generally downwardly so that when the rack is placed adjacent

the interior of the roof 11 of the vehicle, there is general conformation.

Vertical re-enforcing ribs 21 extend between the undersurface of the panel portions 18 and the outer surface of the end wall 14.

The curved end portions are adjustably mounted on panel portions 18 by screws 20 and wing nuts 23 extending through elongated slots 24 in the panel portions 18. Each panel portion 19 includes a clearance slot 25 for the rib 21.

The rack is mounted as shown in FIGS. 1 and 2, preferably immediately behind the front seat with the panel portions engaging the inner surface of the roof 11. The rack is supported either by engaging the end of the panel portions 18 with the conventional flanges 22 of the vehicle or by inserting fastening devices directly through the portions 19 into the roof.

A movable stop 26 of plastic material is provided in slot 17 and has slits 27 so that it can be slidably positioned along slot 17 to prevent the tape cartridges from tipping and rattling.

After the rack is mounted, cartridges C can be inserted in side by side relationship through the opening 16 and readily removed therefrom. To facilitate removal of a particular cartridge from a group, the finger slot 17 is provided through which a finger can be inserted to lift the particular cartridge desired so that it can be grasped and removed from the opening 16. As will be seen in FIG. 2, the rack not only supports the cartridges but does so in a manner that the titles are readily visible through the opening 16. By storing the cartridges adjacent the roof, they are kept out of the way and also away from direct exposure to the sun.

I claim:

1. In a rooftop tape storage rack, the combination comprising
a unitary device molded from organic plastic material
and comprising a top wall, side walls, end walls and
a bottom wall,
at least one of said side walls having a substantially
lesser height than said end walls thereby forming an
opening therein for receiving tape cartridges,
said cartridges being adapted to be held in side-by-
side relationship with the side walls adapted to en-
gage the ends of the cartridges,
a slot associated with the bottom wall and extending
substantially throughout the length thereof provid-
ing a finger receiving opening through which a fin-
ger can be inserted to lift the cartridges for ready
removal from the opening in said side walls,
laterally extending integral mounting panels extend-
ing from said end walls at the area of juncture of
said end walls and said top wall,
said laterally extending panels being curved generally
downwardly with respect to said top wall,
re-enforcing ribs between said panel portions and
said end walls,
extension panels adjustably mounted on said mount-
ing panels,
and a stop adjustably mounted in said slot in said bot-
tom wall for engaging the cartridges,
means on said extension panels for attaching the de-
vice to a vehicle.

2. In a rooftop tape storage rack, the combination comprising

an elongated device comprising a top wall, side walls, end walls and a bottom wall, the length of said walls being many times the width thereof, at least one of said side walls having an opening therethrough for insertion and removal of tape cartridges, a slot associated with said bottom wall and a stop device adjustably mounted along said slot for engaging the endmost cartridge of a series of cartridges, 10 said slot providing a finger receiving opening through which a finger can be inserted to lift the cartridges for ready removal from the opening in said side walls,

15

said cartridges being adapted to be held in side-by-side relation with the side walls adapted to engage the ends of said cartridges, and laterally extending mounting panels connected to and extending from said end walls longitudinally of the device, said panels include extension panels adjustable longitudinally of said device, at least the end portions of said panels being curved generally downwardly with respect to the top wall and being adapted to generally conform with the interior of the roof of a vehicle, and means on said panels for attaching the device to a vehicle.
